ILLUMINATED SIGN

Hyman C. Hammer, Chicago, Ill., assignor to
Price Brothers, Inc., Chicago, Ill.

Application June 3, 1940, Serial No. 338,450

3 Claims. (Cl. 40—130)

The invention relates to improvements in signs and more particularly to an illuminated sign embodying inexpensive means to effect the highly attractive and unique appearance resulting from the use of luminescent tubes.

An object of the invention is to provide a display sign of the character referred to, including a hollow base having a source of illumination therein arranged to illuminate an associated compartment having translucent members associated therewith for direct and indirect illumination by said source.

Another object is to provide an illuminated sign including novel means to sustain translucent members in close association with, but spaced from, a source of illumination concealed within said sign, with the result that when said sign is illuminated, said members will present the effect of luminescent tubes.

Another object is to provide a sign structure of the character described which will be simple to manufacture and assemble and inexpensive to maintain in operation, which may be constructed along lines convenient for low cost production and which will, at the same time, be highly efficient for carrying out the purpose for which it is designed.

The foregoing and such other objects of the invention as will appear hereinafter as the description proceeds, will be more readily understood from a perusal of the following specification, in which reference is made to the accompanying drawing, wherein:

Fig. 1 is a front elevational view of a sign embodying the invention, showing parts broken away to illustrate its interior construction.

Fig. 2 is a vertical sectional view taken substantially on line 2—2 of Fig. 1.

Fig. 3 is a plan view of one end of the sign, showing related parts successively broken away to illustrate the interior construction thereof.

Referring to the drawing, the improved sign includes a hollow base partially defined by a casing 11 having a front wall 12, end walls 13 and a top wall 14. The casing, which may be formed of any suitable material, such as cast metal or the like, has an opening in its bottom which terminates short of the casing ends and normally is closed by a detachably secured bottom plate 15. As best illustrated in Fig. 2, the forward edge 16 of said plate is offset upwardly to engage over the top of an inwardly extending flange 17 on the lower edge of the front wall 12 whereby the forward edge of the plate is retained in position. Screws 18 secure the rear

edge of the plate to the bottom of said casing. As the embodiment illustrated is to be used as a counter sign, the casing 11 may be provided with a plurality of yieldable feet 19 so as to avoid marring any surface upon which the sign may be placed.

Termination of the bottom opening short of the casing ends provides bottom wall portions 21 which extend inwardly a short distance from each end wall 13. The bottom wall portions 21 each provide a mounting for a suitable bracket 22 arranged to carry a conventional lamp socket 23 having conducting cords 24 leading to a source of electric current. The sockets 23 are adapted to receive suitable light bulbs 25 for producing the desired illumination.

An elongated opening 26, provided in the front wall 12 of the casing 11, receives an opaque panel 27 bearing translucent indicia 28. Obviously the panel 27 may be of glass having its entire area, with the exception of the indicia 28 rendered opaque preferably by applying a coating of paint or the like to its rear surface. The indicia 28 may be left clear but it preferably is coated with suitable translucent paint of a color which will contrast with the color of the opaque portion. Consequently, when the lamps 25 are illuminated, the indicia 28 also are illuminated while the remaining portion of the panel does not permit the transmission of light.

A back 29 preferably consisting of a hollow member formed of any suitable material such as sheet metal or the like, is arranged over the open rear side of the casing 11 to define therewith a lower compartment containing the lamps 25. The back 29 has its inside surface coated with a suitable paint or the like to give it a relatively dull finish and it extends upwardly from the casing 11 and is inclined slightly forwardly toward its free edges. The open forward side of said member, extending above the casing 11, has a suitable panel 31 of any transparent sheet material such as for example, clear Celluloid, mounted therein. The panel 31 is disposed substantially in vertical alignment with the lamps 25 and its lower edge is spaced rearwardly from the rear edge of the casing top wall 14, thereby leaving a space 32 between said top wall and panel to permit the passage of light rays laterally through and on both sides of said panel.

One or more strips 33 of translucent light diffusing material, such as Celluloid, glass or any suitable translucent plastic, are arranged along the two vertical margins and the top margin of the panel 31 and preferably are secured thereto

by screws 34. In the disclosure, a single strip 33 is illustrated, said strip being formed substantially in the shape of an inverted U to conform to the outline of the open forward side of the member 29. The strip 33 is shouldered on its outwardly disposed edges to form a seat to receive the free top and end edges of the back 29 when the panel assembly is mounted in place. The overhanging lip 35 formed on said strip by the shoulder conceals the free edges of the back member from view. Although the panel with its mounted border strip 33 may be secured to the back wall in any practical manner, it is preferable that it be anchored by means of spaced screws 36, best shown in Fig. 2.

The panel 31 is provided with desired indicia such as reading matter and the like for advertising purposes. As shown, suitable indicia 37 are arranged on said panel. These members preferably are formed of the same material as the strip 33 and are secured to the front face of the panel 31 by screws or the like 38, or they may be cemented thereto by a translucent adhesive. Upon referring to Fig. 2, it will be noted that the indicia 37 and the marginal strip 33 are of substantially the same thickness and are disposed in vertical alignment with the light opening 31 between the panel and the casing top. Accordingly, illumination from the lamps 25 is directed to the edges of said translucent members and consequently produces an edge-glow incandescent effect when said members are illuminated.

It will be apparent from the foregoing description that when the lamps 25 are connected to a current source, they will illuminate the interior of the base as well as the interior of the upper compartment defined by the extended back and panel with the result that illumination is reflected from the interior surface of the back to increase the panel illumination. It will be noted that objects of this invention are accomplished with a very simple structure containing only a minimum number of parts and a concealed source of illumination. It is to be understood that it is not intended to limit the invention to the specific shape or size of the sign structure illustrated, as the desired effects will be produced by a sign of any size or shape having a compartment to conceal the source of illumination, which compartment is in communication with a second compartment defined in part by a transparent wall having translucent members thereon arranged to be illuminated by the passage of light from the first compartment into the second compartment. The forward wall or transparent panel 31 of the second compartment, when illuminated, is for all practical purposes invisible, due to its clearness and the reflection of the painted interior of the back, while the translucent marginal strip and indicia are highly illuminated by reflected and direct illumination to produce the effect of luminescent tubes suspended in mid air.

I claim:

1. A sign of the character described comprising, in combination, a casing having a top, front and end walls, bottom wall portions extending inwardly from each end wall, a source of illumination mounted in said casing on each bottom wall portion, a detachably secured bottom wall for said casing extending between said bottom wall portions, a back wall secured to said casing and arranged to form therewith a lower compartment, said back wall being spaced from the rear edge of the casing top wall and extending

above said casing, the portion of said back wall above said casing being inclined forwardly and having forwardly turned top and end margins terminating in substantially the same vertical plane as the rear edge of the casing top wall, a transparent panel located in the open forward side of said back wall arranged to form with said back wall an upper compartment in communication with the lower compartment, said panel being disposed in a vertical plane spaced rearwardly from the rear edge of the casing top wall and in substantial vertical alignment with the source of illumination whereby light rays from said source enter the upper compartment and also pass laterally through and in front of said panel, a border of translucent light diffusing colored material on the outside face of the top and end margins of said panel, and indicia of translucent light diffusing colored material on the outside face of said panel, said border and indicia being illuminated by direct light rays passing along the front face of said panel and entering their edges and indirectly by light rays deflected forwardly by the inclined back wall of said upper compartment.

2. A sign of the character described comprising, in combination, a casing having a top, front and end walls, bottom wall portions extending inwardly from each end wall, a source of illumination mounted in said casing on each bottom wall portion, a back wall secured to said casing and arranged to form therewith a lower compartment, said back wall being spaced from the rear edge of the casing top wall and extending above said casing, the portion of said back wall above said casing being inclined forwardly, a transparent panel located in the open forward side of said back wall arranged to form with said back wall an upper compartment in communication with the lower compartment, said panel being disposed in a vertical plane spaced rearwardly from the rear edge of the casing top wall and in substantial vertical alignment with the source of illumination whereby light rays from said source enter the upper compartment and also pass laterally through and in front of said panel, a border of translucent light diffusing colored material on the outside face of the top and end margins of said panel, and indicia of translucent light diffusing colored material on the outside face of said panel, said border and indicia being illuminated by direct light rays passing along the front face of said panel and entering their edges and indirectly by light rays deflected forwardly by the inclined back wall of said upper compartment.

3. A sign of the character described comprising, in combination, a casing having a top, front and end walls, bottom wall portions extending inwardly from each end wall, a source of illumination mounted in said casing on each bottom wall portion, a back wall secured to said casing and arranged to form therewith a lower compartment, said back wall being spaced from the rear edge of the casing top wall and extending above said casing, the portion of said back wall above said casing being inclined forwardly and having an inside light diffusing surface, a transparent panel located in the open forward side of said back wall arranged to form with said back wall an upper compartment in communication with the lower compartment, said panel being disposed in a vertical plane spaced rearwardly from the rear edge of the casing top wall and in substantial vertical alignment with the source of

illumination whereby light rays from said source enter the upper compartment and also pass laterally through and in front of said panel, a border of translucent light diffusing material on the outside face of the top and end margins of said panel, and indicia of translucent light diffusing material on the outside face of said

5 panel, said border and indicia being illuminated by direct light rays passing along the front face of said panel and entering their edges and indirectly by light rays deflected forwardly by the inclined back wall of said upper compartment.

HYMAN C. HAMMER.
